UNITED STATES PATENT OFFICE

170,434

LOUVER PANEL

Esmond Walthall, San Marino, Calif., assignor to
The Kawneer Company, Niles, Mich., a corpo-
ration of Michigan

Application March 24, 1953, Serial No. 24,176

Term of patent 14 years

(Cl. D54—2)

To all whom it may concern:

Be it known that I, Esmond Walthall, a citizen of the United States and a resident of San Marino, county of Los Angeles, State of California, have invented a new, original, and ornamental Design for Louver Panel, of which the following is a specification, reference being had to the accompanying drawing, forming a part hereof.

Fig. 1 is a perspective view of a louver panel, showing my new design; and

Fig. 2 is an end elevational view thereof.

I claim:

The ornamental design for a louver panel, as shown.

ESMOND WALTHALL,
